Specification for Design.

Patented Jan. 4, 1921.

Application filed June 21, 1920. Serial No. 390,664. Term of patent 3½ years.

To all whom it may concern:

Be it known that I, EMILE COSTE, a citizen of the Republic of France, residing at New York, in the county of New York and State of New York, United States of America, have invented a new, original, and ornamental Design for Articles of Manufacture, of which the following is a specification, reference being had to the accompanying illustration, forming part thereof, in which—

The drawing shows in plan view my present design embodied in a piece of fabric.

It is to be understood, however, that my said ornamental design is applicable not

alone to fabrics, but is intended, and is equally well suited for the ornamentation of carpets, wall paper, and similar articles of manufacture having surface ornamentation, without in the least departing from my invention.

I claim as my invention:

The ornamental design for an article of manufacture substantially as shown.

In testimony whereof I subscribe my signature in the presence of two witnesses.

EMILE COSTE.
